OR D 11,477

Design No. 11,477, dated October 28, 1879

UNITED STATES PATENT OFFICE.

CHARLES E. HAVILAND, OF LIMOGES, FRANCE.

DESIGN FOR HOLLOW, FLAT, AND COVERED WARE.

Specification forming part of Design No. 11,477, dated October 28, 1879; application filed October 3, 1879.
[Term of patent 7 years.]

To all whom it may concern:

Be it known that I, CHARLES EDWARD HAVILAND, a citizen of the United States, residing in Limoges, France, have invented a certain Design for Covered and Hollow Ware, and such like articles, of which the following is a full, clear, and exact description and specification, reference being had to the photographic illustration accompanying it, and forming part thereof, in which—

A represents scallops depressed in the surface of the article in substantially parallel or slightly-converging lines, either waving, spiral, or straight in their longitudinal direction, but presenting a uniform appearance. B represents an intertwining cord, raised at some points and depressed or threaded beneath the surface at others, the raised portions serving on some articles to form a handle or handles. It may be either twisted, braided, or plain.

C represents a band running along the base of the article, formed on its lower edge with curves, to provide feet for the dish to stand upon. On the feet are raised spots, as shown.

Parts of the surface of the article may be plain or not, according to the article upon which the scallops or flutes are to be depressed.

Colored figures or pictures may be fixed upon the surface also, if desired.

The article may or may not be provided

with a rim at the outer edge, with or without feet.

What I claim as my invention, and desire to secure by Letters Patent, is—

1. The combination, substantially as herein-before set forth, of an article of hollow or sunken ware, ornamented with uniform depressed scallops and an intertwining cord, substantially as herein described, with the curvilinear band forming feet, all arranged to present the general appearance shown in the photographic illustration.

2. The combination, on an article of hollow or depressed ware, of spiral or straight uniform scallops, with the intertwining cord, substantially as hereinbefore set forth.

3. The combination, substantially as herein-before set forth, of the depressed scallops described, with the curvilinear feet described, placed upon an article of hollow or flat ware, as set forth.

4. The combination of the scallops described, depressed in the surface of hollow, sunken, or flat ware, with said ware arranged substantially in the manner set forth.

CHARLES ED. HAVILAND.
